UNITED STATES PATENT OFFICE

2,596,406

REACTION JET AIRCRAFT PROPELLER
WITH TWO AIR CIRCUITS

Roger J. Imbert, Paris, France, assignor to Societe Rateau (Societe Anonyme), Paris, France, a company of France, and René Anxionnaz, Paris, France, jointly

Application January 27, 1948, Serial No. 4,482
In France February 6, 1947

2 Claims. (Cl. 60—35.6)

1

Double flow reactors or reaction jet propellers have already been described in United States Patent 2,396,911 corresponding to French Patent 864,397 to Societe Rateau and René Anxionnaz, such reactors including a by-pass allowing part of the air removed during compression to pass outside the gas turbine and allowing it to be mixed at the output thereof with the exhaust gases in order to increase their propulsive efficiency.

Figs. 13, 14 and 15 of this prior patent show various forms of execution of such an arrangement allowing the removal of part of the air compressed in the low pressure stages for feeding the high pressure compressors.

It may be of interest when it is desired to increase the dilution output, that is the output of the by-passed air, to resort to a separate compressor for said flux. This arrangement forms the object of the present invention that also includes means for incorporating the dilution compressor in the reactor system.

The following description and accompanying drawing will allow understanding how the invention may be executed, the features appearing either in the specification or in the drawing forming obviously part of said invention. In said drawing:

Fig. 1 is an axial cross-sectional view of a reaction jet turbine the dilution flux of which is fed by a separate axial flow compressor.

Fig. 1a shows a modification of Fig. 1.

Fig. 2 is a cross-section of Fig. 1 through line II—II thereof.

Figs. 3 and 4 are developed cross-sections through lines III—III and IV—IV, respectively, of Fig. 1.

Fig. 5 is an axial cross-sectional view of a modification wherein the dilution flux is fed by a centrifugal compressor with a helical centrifugal wheel.

As apparent from Fig. 1, the diluting compressor includes one or more axial wheels *a*.

Said compressor is mounted on the same shaft line as the high pressure compressor *k* feeding the combustion chamber *h* and the driving gas turbine *t* and consequently rotates at the same speed. The combustion chamber is provided with fuel injectors as shown on the drawing.

The dilution air is delivered by said compressor *a* into an annular duct *c* leading to the upstream end of the reaction nozzle *r* that is supposed to be annular in the present case and that is located immediately beyond the last wheel *b* of the gas turbine *t*.

2

The suction into the compressor *k* of the driving flux is operated through a channel *d* with a circular cross-section.

As shown in Figure 1a, the suction channel *d* for the compressor *k* acting on the driving flux may be prolonged frontwardly so that both compressors *a* and *k* suck air in the same front chamber *l*.

As the channels *c* and *d* should cross one another without hindering the passage of the air and without producing any objectionable disturbances in the fluid flow, the annularly arranged channels *c* are distributed at the points of crossing into sections *e* (Fig. 2) the areas of which are proportional to the outputs to be considered while the annular system *d* is similarly subdivided into sections *f*.

Said sections *e* and *f* appear clearly in Fig. 2 which is a cross-section through line II—II of Fig. 1 registering with the points at which the different channels cross one another.

The channels *c* delivering the flux from the dilution compressor should not lead to any disturbances inside the suction pipes *d* of the compressor of the driving flux and similarly said channels *d* corresponding to the suction into the latter compressor should not be detrimental to the proper flow delivered into the channels *c* by the dilution compressor. To this purpose the different channels should be outwardly streamlined as illustrated in Figs. 3 and 4.

Fig. 3 which is a developed cross-section through line III—III of Fig. 1 shows the passage of the diluting stream between the streamlined channels *f* separating the channels *c* while Fig. 4 that is a developed cross-section through line IV—IV of Fig. 1 illustrates the passage of the driving flux *d* between two stream-lined channel systems *e*.

40 The above described arrangement is not only applicable to axial compressors and it may be executed as well with centrifugal compressors. Fig. 5 illustrates a turbo-reactor executed along the same principles and including a diluting compressor with a helical centrifugal wheel *a* and an axial compressor *k* for the driving flux. As apparent from inspection of said Fig. 5, the arrangement as a whole is but little different from that illustrated in Fig. 1.

45 The advantage of the above described arrangements consists chiefly in the possibility of increasing the output of the dilution stream and of directly driving the dilution compressor *a* by the 50 gas turbine, without speed reducing gear, as

shown on the drawing. This permits a substantial reduction in weight and a simplified construction due to the fact that the speed reducing gear itself, and its auxiliaries such as oil pump, oil tank and oil cooler, are omitted.

The supplementary connecting channels and their fairings that are executed preferably with sheets of light alloy metals reduce only to a small extent the gain in weight referred to.

What I claim is:

1. In a double flow jet propeller comprising a jet reaction system including a nozzle, heating means ahead of said nozzle, and a main air compressor sucking atmospheric air and delivering it towards said heating means and said nozzle, the provision of an auxiliary air compressor sucking atmospheric air and the suction end of which is separate from that of the main compressor, said auxiliary compressor being adapted to feed directly the reaction jet nozzle in by-pass condition with reference to the main flux for diluting same, power means for driving both the main reaction jet feeding compressor and the auxiliary compressor, channels connecting the auxiliary compressor delivery with the reaction jet nozzle, and suction channels feeding the suction end of the main compressor and crossing the last-mentioned channels, the channels of one series allowing the passage between them of the flux passing through the other channels.

2. In a double flow jet propeller comprising a jet reaction system including a nozzle, heating means ahead of said nozzle, and a main air compressor sucking atmospheric air and delivering it towards said heating means and said nozzle, the provision of an auxiliary air compressor sucking atmospheric air and the suction end of which is separate from that of the main compressor, said auxiliary compressor being adapted to feed directly the reaction jet nozzle in by-pass condition with reference to the main flux for diluting same, power means for driving both the main reaction jet feeding compressor and the auxiliary compressor, channels connecting the auxiliary compressor delivery with the reaction jet nozzle, and suction channels feeding the suction end of the main compressor and crossing the last-mentioned channels, the channels of each series being streamlined at their point of passage through the flux of the other series of channels.

ROGER J. IMBERT.
